UNITED STATES PATENT OFFICE.

MATTHEW S. SHANKS AND WILLIAM J. NICKELL, OF CENTERVILLE, IOWA.

FROST-FORMING PREVENTER.

1,249,215.

Specification of Letters Patent.

Patented Dec. 4, 1917.

Application filed January 30, 1917. Serial No. 145,561.

To all whom it may concern:

Be it known that we, MATTHEW S. SHANKS and WILLIAM J. NICKELL, citizens of the United States, residing at Centerville, 5 in the county of Appanoose and State of Iowa, have invented new and useful Improvements in Frost-Forming Preventers, of which the following is a specification.

This invention relates to improvements in 10 devices for preventing the formation of frost upon the inner surfaces of glass windows of locomotives, motor driven cars, cabs and the like, the object being to provide improved devices of this kind which are cheap and 15 simple in construction and which can be readily applied to a window.

The invention consists in the construction, combination and arrangement of devices, hereinafter described and claimed.

20 In the accompanying drawings:—

Figure 1 is a vertical sectional view of a window provided with frost preventing devices constructed and arranged in accordance with our invention.

25 Fig. 2 is an elevation of the same, showing the inner side or rear side of the window.

Fig. 3 is a detailed vertical sectional view on the plane indicated by the line 3—3 of Fig. 2.

30 Fig. 4 is a detailed transverse sectional view on the plane indicated by the line 4—4 of Fig. 2.

The window frame or sash 1 may be of any suitable construction and in accordance 35 with my invention an opening 2 is provided across the upper end of the glass pane 3. As here shown the upper end of the glass pane is spaced from the upper side of the sash or frame to provide said opening 2 but 40 the opening may be otherwise formed or provided within the scope of my invention. On the front or outer side of the sash at the upper end thereof is a hood 4 which extends there-across and also covers the opening 2 and the upper portion of the pane.

On the rear or inner side of the sash at its upper end is a downwardly directed deflector 5 the lower portion of which is spaced to the rear of the upper portion or 50 pane, said deflector being also arranged in rear of the opening 2. Near its ends the deflector is provided with vertical openings

6. A deflector is here shown as constituting

a sheet of metal but may be of any suitable construction.

On opposite sides of the sash at the rear side thereof are vertically arranged ducts 7 which are formed of sheet metal and are provided with out-turned flanges 8 secured to the sides of the sash by nails, screws or 60 other like fastening devices. These ducts contract downwardly and communicate at their upper ends with the openings 6 of the deflector plate so that said openings constitute the air intakes of the ducts. The ducts 65 are closed at their lower ends and also the opposite sides excepting for the provision of narrow air discharge openings 8 at their opposing sides and intermediate and spaced from their upper and lower ends.

In the operation of our improved frost preventing device the current of air which is taken in through the opening at the top of the pane strikes the deflector and is directed downwardly thereby in close 75 proximity to and at the rear side of the pane. Some of the air current also enters the upper ends of the ducts 7 through the openings 6 and the corresponding openings in the sides of the sash and is forced down- 80 wardly through the ducts. Owing to their downwardly contracting construction the ducts accelerate the downwardly directed currents of air therethrough, and the openings in the opposing sides of the air ducts 85 cause air currents to be directed transversely across and in rear of the glass pane so that the rear or inner side of the glass pane is kept at such a low temperature that moist atmosphere in the cab or car is prevented 90 from condensing on the glass panes and hence the formation of frost thereon is also prevented. The hood serves to prevent the entrance of rain, snow, hail or the like as 95 will be understood.

While we have herein shown and described a preferred form of our invention we would have it understood that changes may be made in the form, proportion and construction of the several parts, without departing 100 from the spirit of our invention and within the scope of the appended claim.

Having thus described our invention, what we claim is:—

In a window, a progressively downwardly contracting duct arranged on the rear or

inner side of the window at one side of the glass pane and provided at one side with a narrow air discharge opening extending along the greater part of the length of the 5 duct to direct air currents transversely across the rear or inner side of the pane, said duct having an air intake opening at

its upper larger end and being closed at its lower end.

In testimony whereof we affix our signatures.

MATTHEW S. SHANKS.
WILLIAM J. NICKELL.
